(57) **CLAIM**

The ornamental design for an electric connector, as shown and described.

DESCRIPTION

FIG. 1 is a rear perspective view of an electric connector according to the invention.

FIG. 2 is a front view of the electric connector of FIG. 1.

FIG. 3 is a rear view of the electric connector of FIG. 1.

FIG. 4 is a left side view of the electric connector of FIG. 1.

FIG. 5 is a right side view of the electric connector of FIG. 1.

FIG. 6 is a top plan view of the electric connector of FIG. 1; and,

FIG. 7 is a bottom plan view of the electric connector of FIG. 1.

The broken lines shown in the drawings are included for the purpose of illustrating portions of the article which form no part of the claimed design.

1 Claim, 5 Drawing Sheets(56)
